UNITED STATES PATENT OFFICE.

JOHN HILL, OF COLUMBUS, GEORGIA.

AUTOMATIC FIRE-ALARM.

SPECIFICATION forming part of Letters Patent No. 295,760, dated March 25, 1884.

Application filed September 10, 1883. (No model.)

To all whom it may concern:

Be it known that I, JOHN HILL, a citizen of the United States, residing at Columbus, in the county of Muscogee and State of Georgia, have 5 invented new and useful Improvements in Automatic Fire-Alarms, of which the following is a specification.

This invention relates to improvements in fire-alarms, and has for its object to provide 10 novel, simple, and efficient means for automatically closing an electric circuit by the generated heat of a conflagration, thereby sounding an alarm.

To this end my invention consists in the 15 combination of devices hereinafter described and claimed, reference being had to the accompanying drawings, illustrating the invention, in which—

Figure 1 is a plan of the case or box inclosing the automatic circuit-closing apparatus. Fig. 2 is a central longitudinal section of Fig. 1, showing the circuit open. Fig. 3 is a similar section, showing the circuit closed. Fig. 4 is a plan view of the inclosing-case shown in 25 Figs. 2 and 3 inverted. Figs. 5, 6, 7, and 8 are plan and side elevations, respectively, of the electric connections contained within the casing. Figs. 9 and 10 are central sections of the inclosing-case, showing a modified form 30 of the copper disk with the manner of attaching the same to the case. Figs. 11 and 12 are sections of the copper disk detached, showing its form before and after attachment to the case. Fig. 13 is a section of the circuit-closer 35 combined with a journal or other bearing.

The device which forms the subject-matter of this application consists of an outer box or casing, *a*, with its open side lying upon a foundation or bed-plate, *a'*, to which it is securely 40 fastened, whereby said casing is completely closed, with the exception of a single opening in the top of said casing, which is adapted to receive a fusible solder joint and plug, *x*. At 45 at one end of said casing, and arranged longitudinally therewith, I attach a flat strip of conducting metal, *L'*, having a platinum contact-point, *y*, near one end, which extends within the casing *a*, and is firmly secured to the bed or back *a'* by means of a screw, *b*, which 50 also serves as a binding-post for the circuit-wire *c*. The plate *L'* may be provided with perforations to receive screws, whereby it is

fastened to the upper casing, *a*, in which construction the single screw *b* will serve to attach said casing to the base or support *a'*, as 55 shown in Fig. 2. At the opposite end of said casing, and in the same longitudinal line with the strip *L'*, is placed an elastic conducting-strip, *K*, attached to said casing and to the back piece, *a'*, in a manner similar to that al- 60 ready described in connection with the strip *L'*, and having a contact-point, *d*, which is so arranged that when the strip *K* assumes its natural position said contact will rest upon the contact *g*. The second circuit-wire, *c'*, is 65 connected with the strip *K* by means of the binding-post *b*, which also serves to hold the casing *a* firmly in place upon the back piece, *a'*. Screws may also be passed through the latter into the casing *a*, in order to make a 70 close joint between the two and prevent the entrance of dust, the presence of which should be avoided in all apparatus of this class.

In the top of the case *a*, and directly in line with the conducting-strips *K L'*, is placed an 75 annulus, *W*, which may be made of any suitable material, that I prefer being a convex copper disk, as shown in Figs. 9 and 10, having its center removed so as to leave an opening about one-eighth of an inch in diameter. 80 This convex annulus is constructed in the following manner: A thin copper disk having a central opening is drawn by dies or other suitable means into a convex form, as shown in Figs. 9 and 11, its diameter being such 85 that it will accurately fill the countersunk recess *a''*, the central opening in the disk being practically concentric with the opening *a'* in the case *a*. A hollow punch having an outer diameter about equal to that of the disk is 90 then placed upon it, and by a blow of a mallet the outer annular portion of the convex disk is flattened, as shown in Figs. 10 and 12. By this operation the edge of the disk, which is expanded radially, is driven into the wood of 95 the case *a*, fastening the disk firmly in place and sealing the case against the entrance of dust. The central portion of the disk is left convex and projecting somewhat above the top of the casing. The opening *a''* in the case 100 *a* is concentric with that in the annulus *W*, but of smaller diameter. It will be noticed that the end of the strip *K* projects some little distance beyond the contact-point *d*, and upon

the upper face of this projecting end is mounted a cylindrical projection, Y, considerably smaller than the opening in the casing, but too large to pass through that in the annulus W. 5 The contact-points *d* and *g*, being separated by raising the elastic strip K, the projection Y is forced up into the aperture in the case *a* and against the lower face of the annulus W. While in this position a drop of solder, *x*, is 10 allowed to fall into the opening in the annulus, through which it passes until it comes in contact with the projection Y, to which it attaches. The solder-plug, upon becoming solid, as it does almost instantaneously, 15 surely holds the strip K in the position shown in Fig. 2, thereby keeping the circuit permanently broken at that point. Whenever said plug is fused, however, the projection Y is released, and the elasticity of the strip K im- 20 mediately brings the contact-point *d* down upon the point *g*, thereby closing the circuit and giving the alarm. Attention is called to the fact that the application of the solder- 25 plug X seals the casing *a*, tightly closing the only aperture left therein after it is applied to the back piece, *a'*.

The solder-plug X is made of a combination of various metals, the object thereof being that it shall fuse at a comparatively low tempera- 30 ture, ranging from 110° to 212° Fahrenheit. Heretofore a composition has been used consisting of lead, tin, and cadmium, which would melt at 155° to 160° Fahrenheit, and in localities where fusion is not required at lower tem- 35 peratures, I use the same. In many places, however, a much lower fusion-point is desir- able, ranging as low as 110° Fahrenheit. For the latter temperature I use a composition consisting of the several metals named above, 40 with a small portion of mercury, and thereby obtain a solder which will readily fuse at tem- peratures far below any composition heretofore made and used for this purpose—viz., 110° to 140° Fahrenheit. The quantity of 45 mercury employed depends upon the point at which fusion is required, the greater the pro- portion thereof the lower being the point of fusion. By setting the solder-plug in a thin copper disk and blackening the latter, rapid 50 absorption of heat is obtained, and the automatic circuit-closer is rendered more rapid and reliable in action.

These devices may be scattered in as many localities as may be desired, the wires *c* and 55 *c'* being connected to the wires of the main circuit, or to branch wires leading therefrom. The breaking out of a fire at any one of these points creates sufficient heat to fuse the solder- 60 plug and release the spring-connection K, which at once falls upon the connection L', each arm having a contact-point. The circuit is thereby closed and the current flows from bat- 65 tery over the line, actuating the electric alarms interposed in the circuit.

65 Although I preferably use the thin convex disk shown in Figs. 9, 10, 11, and 12, I may use the flat copper annulus W shown in Figs.

1, 2, and 3. The thin convex disk named may be pressed into the recess *a'* and secured without expansion by being simply cemented in 70 place; or a projection may be substituted for the recess, and the edges of the disk fitted around such projection as a band, and be thus secured in place.

Although these circuit-closers are adapted 75 for general use to indicate the outbreak of fire, sound the alarm, and designate the locality in the manner described in my application for Letters Patent filed upon the 22d day of May, 1883, there are other and most important uses 80 to which it may be put, of which the following is an example: It is well known that in all mills and large manufacturing establish- 85 ments there are a great number of journal and other bearings which are not only secluded from observation, but which, from their number alone, cannot be constantly watched. It is a common occurrence for fires to ignite from the heat generated from friction at such points. Even when the damage resulting is not great, 90 the loss of time in a large establishment from the stoppage of the machinery is a serious consideration. I propose, therefore, to use this sensitive circuit-closer at all points where 95 there is frictional contact which might, under favorable circumstances, heat the parts to the point of ignition of surrounding material, and to employ a fusible plug or solder-joint which shall melt at a point considerably below the point of combustion—as, for example, at 212° 100 Fahrenheit. The circuit-closer may be attached to the journal-boxes or contiguously thereto in such manner that the heat therefrom may be communicated to the solder-joint 105 easily and without delay. Each bearing may be supplied with one of these circuit-closers, and the wires may be carried to any desired point where it is expedient to sound the alarm and designate the locality of the heating jour- 110 nals.

The casing *a* is closed and sealed, as already 115 described, and is impervious to oil and water, as they are arranged in places where they may be subjected to and possibly covered with either.

With this invention, applied in the manner 120 described, fires from overheated journals will be practically impossible.

My invention may also be applied to rail- 125 way-trains, to steamships, and other places.

The size of the copper disk W may, if re- 130 quired, be varied, the apparatus being ren- dered more sensitive by increasing its super- ficial area within certain limits.

I also propose to use, in some instances, a 135 metallic casing having insulated attachments for the electric connections, whereby oil will be wholly excluded from the interior of the casing *a*.

I am aware that it is not new in an auto- 140 matic fire-alarm to hold an elastic conductor out of contact with a stationary conductor by means of fusible material; and such, therefore, I do not broadly claim.

Having thus described my invention, what I claim is—

1. In an automatic fire-alarm, the combination of two conductors, one of which is composed of an elastic metal, with a metallic disk, means for supporting the disk in a stationary position at one side of the elastic conductor, and a fusible joint connecting the latter with the stationary disk, to hold the said elastic conductor out of contact with the other conductor, substantially as described.
2. An automatic circuit-closer contained in a closely-sealed case, and consisting of electric connections which enter said case and are normally in contact, but which are held out of contact by a fusible plug which enters and seals an aperture in the top, from which it is exposed, substantially as described.
3. An automatic circuit-closing device, consisting of the conductors K and L, having suitable contact-points, said points being contained within a casing, *a a'*, and being held out of contact by means of a fusible plug, X, ex-

posed upon the outside of said casing *a*, substantially as described.

4. The combination, in an automatic fire-alarm, of a case having a recess, a sensitive disk having a convex center and a flat surrounding margin, and arranged in the recess, the conductors, and a fusible joint, substantially as described.

5. The combination, in an automatic fire-alarm, of a disk having a perforation, a conductor, L, having a contact-point, an elastic conductor having a contact-point on one side and a projection on the opposite side, and a fusible plug passing through the perforation in the disk for connecting the said projection with the disk, substantially as described.

In testimony whereof I have hereunto set my hand in the presence of two subscribing witnesses.

JOHN HILL.
